Des. 236,544
Patented Aug. 26, 1975

236,544

MICROFORM VIEWER

Norbert T. Kuypers, Lake Orion, Mich., assignor to
Xerox Corporation, Stamford, Conn.

Filed Jan. 8, 1973, Ser. No. 321,892

Term of patent 14 years

Int. Cl. D16—03

U.S. Cl. D61—1 N

FIG. 1

FIG. 2

FIG. 3

FIG. 7

FIG. 4

FIG. 5

FIG. 6

FIG. 1 is a front perspective view of a microform viewer showing my new design with the support in the raised position;

FIG. 2 is a front elevational view thereof;

FIG. 3 is a top plan view thereof;

FIG. 4 is a right side elevation view thereof;

FIG. 5 is a left side elevation view thereof;

FIG. 6 is a rear elevational view thereof; and

FIG. 7 is a bottom plan view thereof.

I claim:

The ornamental design for a microform viewer, as shown.
